UNITED STATES PATENT OFFICE.

JOHANNES KRÜGER, OF OSTERHOLZ-SCHARMBECK, GERMANY.

SLIDE-VALVE GEAR.

Application filed June 1, 1921. Serial No. 474,258.

(GRANTED UNDER THE PROVISIONS OF THE ACT OF MARCH 3, 1921, 41 STAT. L., 1313.)

To all whom it may concern:

Be it known that I, JOHANNES KRÜGER, a citizen of the German Empire, residing at Osterholz - Scharmbbeck, Germany, have invented certain new and useful Improvements in Slide-Valve Gears, for which I have filed application in Germany, May 27, 1920, Patent No. 331,304, and of which the following is a specification.

10 My invention refers to slide valve gear for steam engines and its particular object is to automatically arrest such valve gear in its end positions.

Slide valve gears for steam engines, and 15 more especially for steam pumps in which the distributing valve is controlled by the steam which at the end of the stroke flows from the working cylinder into a chamber 20 at the front of the distributing valve 25 through a passage which in the end position of the piston is opened by the latter, have already been made use of. There are further known steam engine valve gears with two working pistons mounted on the 30 same piston rod and a chamber intermediate these pistons connected to the exhaust, this chamber communicating alternately with either of the front chambers of the piston valve. Engines controlled in this 35 manner offer the advantage of simple and cheap construction. The disadvantage of the hitherto known designs of this kind, however, is that the distribution valve is held in an inadequate manner in its end 40 positions on the one or other frontal side. In the center position of the working piston of a steam engine of this type, exhaust steam acts on both sides of the distribution valve, so that this distribution valve is 45 not held fixedly in position. Thus it may happen that on board ship the piston valve may be set in motion by the rolling of the vessel whereby the valve gear may be reversed at the improper moment.

50 In order to overcome this difficulty, i. e. not only to effect the required movement of the controlling piston, but also to keep the latter in the required end position, I provide that the controlling piston at its two frontal sides, besides being under the influence of the frontal chambers hitherto used, is also acted upon by auxiliary steam chambers which have a smaller sectional area than the remaining effective frontal

surface of the controlling piston and which 55 are connected to the main admission ducts of the steam cylinder in such a manner that each time the one particular steam chamber which happens to be opposite to the required end position of the controlling 60 piston is supplied with live steam. Therefore, according to the present invention, the control valve is secured in the respective end position by the reliable medium of live 65 steam.

In the drawings affixed to this specification and forming part thereof three modifications of a device embodying my invention are illustrated diagrammatically by way of example. In the drawings— 70

Fig. 1 is a longitudinal section of the first modification,

Figs. 2 and 3 being similar views showing 75 the parts in different positions of the second modification which differs from the first modification in a detail regarding the steam conduits, while

Fig. 4 is a longitudinal section of the third modification differing from Fig. 1 with regard to the slide valve. 80

Referring first to Figs. 1 to 3 the modification shown in Figs. 2 and 3 is identical with the one illustrated in Fig. 1, excepting only the manner of connecting certain steam conduits which shall be described 85 more particularly hereinafter. In all other points, the following description of the design and manner of operating refers to both modifications. In both of them, N is the working cylinder, K₁ and K₂ are the two 90 working pistons arranged on a common piston rod R, and M is the valve box provided with a lining P of a well known kind. Live steam enters through a central inlet 17, while the exhaust steam escapes through lateral 95 conduits 10 and 11. The lateral or end portions C and D of the valve box M are connected with the central portion of the working cylinder N by conduits 3 and 6, whereby the live steam is caused to shift in 100 a well known manner, which is more fully described hereinafter, the piston slide valve E from one to the opposite positions, whenever the working pistons K₁ and K₂ approach their end positions. The slide valve 105 E is provided at either end with a cylindrical cavity or chamber A and B, respectively, which may be termed "auxiliary

chambers", their cross section being smaller than the remaining end surfaces of the slide valve in the chambers C and D. The chambers A and B are closed by stationary pistons Q_1 and Q_2 , respectively, fixed to the valve box covers. In the modification shown in Fig. 1 chamber A is connected by a conduit 4 directly with the main steam passage 2, chamber B by a conduit 5 directly with the main steam passage 1, while in the modification shown in Figs. 2 and 3 chamber A communicates by way of a conduit 4 with an aperture of the valve box M disposed near the level of the upper end of the main steam passage 2, and chamber B is connected by a conduit 5 with an aperture disposed near the level of the main steam passage 1, the chambers A and B being thus connected in both forms crosswise with the main steam canals 2 and 1, respectively, the lefthand auxiliary chamber A with the righthand passage 2 and the righthand auxiliary chamber B with the lefthand passage 1.

The operation of this device is for both forms the following:—

Assuming the slide valve E shown in Fig. 1 not to assume the middle position illustrated, but the right hand end position shown in Fig. 1 the double piston K_1 , K_2 is on its way from the right to the left. In this right hand end position of the slide valve E live steam enters through the central inlet 17 and steam passage 2 into the righthand end portion of the working cylinder and causes the working piston to move to the left, while exhaust steam escapes from the working cylinder through passage 1 and the lefthand exhaust opening 10 of the valve box M. The righthand end portion D as well as the lefthand end portion C of the valve box communicate by the conduits 3 and 6, respectively, with the space between the two pistons K_1 and K_2 , which is connected by canal 12 with the righthand exhaust steam opening 11, whereby D and C are under exhaust steam pressure also. The righthand auxiliary chamber B of the slide E communicates by conduit 5 with the exhaust steam canal 1 and is therefore under exhaust steam pressure as well. On the other hand the lefthand auxiliary chamber A of the slide communicates through conduit 4 with the live steam passage 2, whereby the slide is held immovably in the righthand end position shown in Fig. 2 by the live steam in chamber A.

When the working pistons K_1 , K_2 reach the position illustrated in Figure 2, the righthand end space D of the valve casing M is connected through conduit 3 with the live steam in the righthand end space of the working cylinder N, whereas the steam-connections in the other chambers A, B and C remain at first the same, as described with

reference to Figure 1. Thus, the righthand auxiliary chamber B and the lefthand end space C is under exhaust steam pressure, while in the lefthand auxiliary chamber A and the righthand end space D there prevails live steam pressure. Inasmuch, however, as the effective end surface of the slide valve in the end space D is larger than the surface of the auxiliary chamber A, which counteracts it, the slide valve E will be shifted into the lefthand end position shown in Figure 3 and the piston of the engine will thereby be reversed, so that now live steam enters through passage 1 into the lefthand end space of the working cylinder N and acts on the piston K_1 , while the righthand end space of the working cylinder is connected through passage 2 with the exhaust steam sleeve 11. In consequence thereof also the righthand end space D, which is connected through port and conduit 3 with the righthand end space of the working cylinder, and the lefthand auxiliary chamber A, which communicates through conduit 4 with the exhaust steam passage 2, are under exhaust steam pressure. The same is true of the lefthand end space C, which remains in connection through conduit 6 with the space between the two pistons K_1 and K_2 , which is permanently under exhaust steam pressure. On the other hand, the righthand auxiliary chamber B now communicates through conduit 5 with the live steam passage 1. Therefore, in the position of parts shown in Figure 3, exhaust steam pressure exists in the two end chambers C and D, as well as in the auxiliary chamber A, whereas live steam pressure exists in the righthand auxiliary chamber B, so that now the slide valve is retained in its lefthand end position by the live steam in the righthand auxiliary chamber B.

These conditions remain unchanged until the piston K_1 , in moving from the left to the right, uncovers the port and conduit 6, whereby the lefthand end space C is connected with the lefthand end space of the working cylinder, which is under live steam pressure, so that live steam enters the space C. On the other hand, the steam conditions in the chambers A, B and D remain at first unchanged, that is to say, the auxiliary chamber A and the end space D are under exhaust steam pressure, the end space C and the auxiliary chamber B under live steam pressure. However, as the effective end surface of the slide valve in chamber C is larger than the surface in the auxiliary chamber B which counteracts it, the slide valve is now shifted from the lefthand end position of Figure 3 into the righthand end position, the engine being thereby reversed, so that now the righthand end space of the working cylinder is connected through pas-

sage 2 with the live steam inlet 17, the left-hand end space through passage 1 with the exhaust through 10, while the steam conditions in the chambers A, B, C and D are 5 now changed as described with reference to Figure 1, that is to say, exhaust steam pressure now exists in the end space D, which is connected through conduit 3 with the space between the two pistons K_1 and K_2 , 10 as well as in the auxiliary chamber B communicating through conduit 5 with the exhaust steam passage 1, and in the end space C which is now connected through conduit 6 with the exhaust steam side of the working cylinder, while the auxiliary chamber A communicating through conduit 4 with the live steam passage 2 is under live steam pressure, so that the slide valve is immovably retained in its righthand end position. 15 20 The modification disclosed in Figure 4 is substantially identical with the first modification illustrated in Figure 1 with the exception that in the modification of Figure 4 the two auxiliary chambers A and B are not arranged in the slide valve, but in the two covers of the valve casing, while the pistons Q_1 and Q_2 form part of the slide valve. The cross sectional area of the auxiliary chambers A and B and the effective surface 25 30 of the auxiliary pistons Q_1 and Q_2 is here as well smaller than the remaining effective surface of the slide valve in the end spaces of the valve casing. The lefthand auxiliary chamber is again connected 35 through conduit 4 with the righthand steam passage 2, the righthand auxiliary chamber B through the conduit 5 with the lefthand steam passage 1, both conduits 4 and 5 extending down to the passages 2 and 1. The 40 mode of operation and the effect of this modification is the same in all respects as described with reference to the modifications illustrated in Figures 1-3 and it is, therefore, unnecessary to once more describe it. 45

I claim:

1. In a steam engine in combination, a cylinder, a double piston adapted to reciprocate within said cylinder, a distributing slide valve, and an exhaust port adapted to be connected with said cylinder by said valve, a chamber at each end of said valve adapted to be connected with the exhaust through the space enclosed by said double piston and near the end of the piston stroke with the live steam space of said cylinder for throwing the valve, an auxiliary chamber of smaller sectional area than the effective surface of said slide valve at each end of said valve, a piston fitting in and forming a closure for each auxiliary chamber and a special connection, adapted to be controlled by said slide valve, between each auxiliary chamber and the live steam space on the opposite side of said cylinder for retaining the valve in thrown position. 55 60 65

2. In a steam engine in combination, a cylinder, a double piston adapted to reciprocate within said cylinder, a distributing slide valve a casing for said valve and an exhaust port adapted to be connected with said cylinder by said valve, each end of said valve casing being adapted to be connected with the exhaust through the space enclosed by said double piston and, near the 70 end of the piston stroke with the live steam space of said cylinder for throwing the valve, an auxiliary chamber of smaller sectional area than the effective surface of said slide valve at each end of said valve casing, a piston integral with said valve fitting in and forming a closure for each auxiliary chamber, and a special connection, adapted to be controlled by said slide valve between each auxiliary chamber and the live steam space on the opposite side of said cylinder for retaining the valve in thrown position. 75 80 85

In testimony whereof I affix my signature.

JOHANNES KRÜGER.
